UNITED STATES PATENT OFFICE.

JAMES G. MERRIMAN, OF ROME, NEW YORK, ASSIGNOR TO THE ROME
MALLEABLE IRON WORKS, OF SAME PLACE.

DESIGN FOR A HARNESS-SADDLE.

SPECIFICATION forming part of Design No. 16,867, dated August 24, 1886.

Application filed June 9, 1886. Serial No. 204,682. Term of patent 7 years.

To all whom it may concern:

Be it known that I, JAMES G. MERRIMAN, a citizen of the United States of America, residing at Rome, in the county of Oneida and State of New York, have invented and produced a new and original Design for Harness-Saddle Trees, known as "Express Trees," of which the following is a specification, reference being had therein to the accompanying drawings.

My invention relates to a new design for a harness-saddle having beveled edges of a color different from the color of the other surfaces of the saddle, as hereinafter fully set forth and claimed.

In the accompanying drawings, showing my new design, Figure 1 is a perspective view. Fig. 2 is a plan view. Fig. 3 is an edge view, and Fig. 4 a cross-section on line $\alpha\alpha$ of Fig. 2.

The upper surfaces of the seat A, the cantle B, and the interior portions, C, of the skirt-plates are of a dark color. The front edges, b , of the entire saddle, the back edges, $c c$, and bottom edges, $d d$, of the skirt-plates are beveled, as shown, and the color of these beveled edges differs from the color of the other surfaces of the saddle sufficiently to be readily perceptible and to form an aesthetic design for a harness-saddle.

What I claim as new is—

The design herein shown and described for a harness-saddle, having the beveled surfaces $b c d$ and the other surfaces, A B C, the color of the beveled surfaces being different from the color of the other surfaces of the saddle, as set forth.

In testimony whereof I affix my signature in presence of two witnesses.

JAMES G. MERRIMAN.
